United States Patent Office.

T. W. M. CASTLE AND J. B. CONNER, OF ADRILACE, INDIANA.

Letters Patent No. 79,053, dated June 23, 1868.

IMPROVEMENT IN PRINTING-PRESS FRISKETS.

The Schedule referred to in these Letters Patent and making part of the same,

TO ALL WHOM IT MAY CONCERN:

Be it known that we, T. W. M. CASTLE and J. B. CONNER, of Adriance, in the county of Newton, and State of Indiana, have invented a new and improved Frisket; and we do hereby declare that the following is a full, clear, and exact description thereof, which will enable others skilled in the art to make and use the same, reference being had to the accompanying drawings, forming part of this specification.

This invention relates to a new and improved frisket for printing-presses; and it consists in a novel construction and application of the former to the tympan of a press, as hereinafter fully shown and described, whereby the frisket is operated, opened, and closed automatically, by the raising and lowering of the tympan.

In the accompanying sheet of drawings—

Figure 1 is a front or face view of our improvement, the frisket being in a raised position.

Figure 2, a longitudinal vertical section of the same, the frisket being in a downward position. *xx*, fig. 1, is the line of section.

Figure 3, a longitudinal section of fig. 1, taken in the line *yy*.

Similar letters of reference indicate corresponding parts.

A represents a tympan of a printing-press, which is connected at one end, as usual, to the bed *B* by hinges, *aa*. *C C* are two shafts attached to the inner or face side of the tympan, or near each side or edge of the same, said shafts being allowed to turn freely in bearings, *b*, secured to the front and inner ends of the tympan, (see figs. 1 and 2.)

The frisket is composed of two parts, *D D*, attached one to each shaft, *C*, and they are narrow strips of sheet metal, or narrow frames covered with any suitable fabric.

We do not confine ourselves to any particular construction, nor to any particular material, in making the frisket.

On each shaft, *C*, near its inner end, is placed a spiral spring, *E*, and these springs have a tendency to keep the outer ends of the parts *D D* of the frisket in contact with the inner surface of the tympan, and on the inner end of each shaft, *C*, there is keyed a pulley or half pulley, *F*, to which cords, *c c*, are attached, the outer ends of said cords being secured to the outer ends of two levers, *G G*, which have their fulcras, *d d*, attached to the inner end of the tympan.

To the rear end of the bed *B* there are attached two upright curved prongs, *e e*, which are located at such points that when the tympan *A* is raised and thrown a trifle back of a vertical position, the levers *G G* will come in contact with said prongs, and be actuated so as to throw outward the two parts *D D*, comprising the frisket, so that a printed sheet may be taken therefrom and a blank sheet inserted in its place, the blank sheet being grasped and held by the two parts *D D* of the frisket as soon as the tympan is turned up to a vertical position, which relieves the levers *G G* from the prongs *e e*, and admits of the springs *E E* throwing the two parts *D D* of the frisket inward, so as to grasp the blank sheet.

By this very simple arrangement the frisket is operated automatically by the raising and lowering of the tympan, and a printing-press, therefore, may be manipulated with much greater facility and expedition than hitherto.

We claim as new, and desire to secure by Letters Patent—

Constructing the frisket of the parts *D D*, attached to the tympan *A*, substantially as shown, in combination with the pulleys or semi-pulleys *F*, springs *E*, levers *G G*, and the prongs *e e*, all arranged and applied to operate in the manner substantially as and for the purpose set forth.

T. W. M. CASTLE,
J. B. CONNER.
